UNITED STATES PATENT OFFICE

CHARLES R. HULTGREN, OF CHICAGO, ILLINOIS, ASSIGNOR TO S. KARPEN & BROS., OF CHICAGO, ILLINOIS, A CORPORATION OF WEST VIRGINIA

SOFA BED

Application filed February 7, 1927. Serial No. 166,386.

This invention relates particularly to sofa-beds and constitutes a modification of the invention described in my application, Serial No. 165,557, filed Feb. 3, 1927.

5 The primary object of the present invention is to make provision, in the type of construction illustrated, for sufficient clearance between the bed-sections in the closed condition and in the opening and closing operations to accommodate a mattress, or bedding, between the bed-sections.

In the improved construction which is illustrated in the accompanying drawings, the rear bed-section is mounted on the short arms 15 of two pairs of angular levers, one pair being located at each end of the main frame, and the front bed-section is mounted on the long arms of said levers. Provision is made, however, for giving to one of the bed-sections a 20 tilting movement followed by a leveling movement during conversion of the structure from sofa-form to bed-form and vice versa. The relative movements of the two bed-sections are so regulated through the medium 25 of the connections as to insure clearance between the rear lower corner of the front bed-section and the upper front corner of the mattress, or bedding, in the opening and closing movements of the structure.

30 The preferred embodiment of the invention is illustrated in the accompanying drawings, in which—

Fig. 1 is a broken vertical sectional view of the improved sofa-bed in extended condition; Fig. 2, a similar sectional view with the upholstery springs and mattress removed; Fig. 3, a view similar to Fig. 2, but illustrating the position of the parts at a critical point while the rear portion of the front bed-section is being carried past the front portion of the folded mattress; Fig. 4, a sectional view of the structure in folded condition, this view showing in dotted lines a seat-cushion which does not appear in the other views; Fig. 5, a view similar to Fig. 3, but showing the bed-section in another position; Fig. 6, a broken plan sectional view taken as indicated at line 6 of Fig. 2; Fig. 7, a broken vertical sectional view taken as indicated at line 7—7 50 of Fig. 2; and Fig. 8, a broken vertical sec-

tional view taken as indicated at line 8—8 of Fig. 2.

In the description which follows, it is to be understood that the views illustrate the construction at one end of the sofa-bed structure, and that the parts are duplicated at the other end of the structure.

In the construction illustrated, A designates a main frame provided with end-standards A' (one shown), a back A², rear longitudinal connecting members A³, and a front longitudinal connecting member A⁴; B, a pair of mounting-bars (one at each end of the structure, only one being shown, however), these mounting-bars being carried in a well known manner on bracket-plates B' which are secured to the inner surfaces of the end-standards A' near their lower front corners; C, a pair of front angular levers (one shown) having their short arms connected by pivots 1 to the front portions of the mounting-bars and having their long arms connected by pivots 2 with the front bed-section; D, a pair of rear angular levers having their short arms connected by pivots 3 with the mounting-bars and having their long arms connected by pivots 4 with the rear portion of the front bed-section; E, a front bed-section carried by the long arms of the angular levers and shown equipped with a spring bed-bottom E'; F, a rear bed-section 60 slidably mounted on guides, or clips, 5 and 6 which are connected, respectively, with the elbow-portions of the front angular levers and the rear angular levers by pivots 5^a and 6^a, the rear bed-section being shown equipped with a spring bed-bottom F'; G, a folding mattress mounted on the spring bed-bottoms; H, a pair of control links (one shown) 65 connected with the rear bed-section by pivots 7 and with the rear angular levers by pivots 8; I, counterbalance springs connected at their rear ends with studs 9 carried by the rear ends of the mounting-bars and connected at their front ends by studs 10 with lugs 11 with which the rear angular levers are equipped; J, legs connected by pivots 12 with the front portion of the front bed-section; and K, links controlling the movements 70 of the legs, said links being connected at 75

their rear ends by pivots 13 with the long arms of the front angular levers and being connected at their front ends by pivots 14 with short extensions with which the legs 5 are equipped at their upper ends.

The main frame of the sofa-bed may be of any desired construction. In the illustration given, it is to be understood that the end-standards A' are rigidly connected together by the rear connecting members A³ and by the front connecting member A⁴.

The bracket-plates B' are rigidly secured to the end-standards of the frame, as by means of screws 15; and the mounting-plates 15 B are equipped with studs 16 which engage slots 16^a with which the bracket-plates are provided. The mounting-plates are additionally secured to the main frame by means of screws 17.

20 The front angular levers C are rigidly connected together by a bar 1^a whose end-portions form the pivots 1 which are connected with the mounting-plates B, as shown in Fig. 8. The pivots 5^a with which the slides 5 are equipped are of sufficient length to form stops on which the long arms of the rear angular levers can rest when the structure is in extended condition, as shown in Fig. 8. Pivots 5^a can turn either in the front levers C or in the clips 5, or both.

As may be seen from Fig. 3, for example, the short arms of the front angular levers are, in the illustration given, of less length than the short arms of the rear angular levers; also, the short arms of the front bell-crank levers are non-parallel with the short arms of the rear angular levers. In other words, the front pair of short arms are at an angle with respect to the rear pair of short arms. This will be understood by noting the angle between the dotted line 18—18 and the dotted line 19—19 passing through the pivotal centers.

It will be noted that when the structure 45 is unfolded from the condition shown in Fig. 4, the slide 6 will be elevated more rapidly than the slides 5, and thus the rear bed-section will occupy a forwardly and downwardly tilted position at the time that the rear 50 portion of the rear bed-section is passing the front portion of the folded mattress or bedding, it being noted from Fig. 4 that in the completely folded condition of the structure the mattress G, in folded condition, is housed 55 between the upper and lower bed-sections. The relative positions of the front and rear bed-sections at the critical point when the rear corner of the front bed-section is passing the front corner of the bedding is shown 60 in Fig. 3. Because of the tilted condition of the rear bed-section, ample clearance is provided.

It should be added that when the structure moves from the position shown in Fig. 2 or the position shown in Fig. 4, the lower

bed-section is brought into a position substantially parallel with the upper bed-section. What may be termed the undulatory movement of the rear bed-section during its translation is due to the variation in the 70 lengths of the short arms of the front and rear levers and to the fact that the pivot-points 5^a and 6^a are describing different portions of their respective arcs during the turning movement of the levers. In other words, 75 the connections between the levers and the rear bed-section describe non-parallel paths in the operation of converting the structure. When the structure is in the extended position shown in Fig. 2, the short arms of the 80 front levers incline rearwardly somewhat and the short arms of the rear levers incline forwardly somewhat, so that a mutual bracing results which serves to prevent the structure from collapsing when the bed is occupied. 85

The control links H serve to keep the rear bed-section properly located on the slides 5 and 6, permitting only limited shifting movement of the bed-section on the slides during the operations of opening and closing the 90 structure. The counterbalance springs I are placed under tension in both the open and closed positions of the structure.

The links K serve to actuate the legs J in a well known manner.

In Fig. 4, L designates a loose seat-cushion which is supported by the spring-bottom E' of the front bed-section when the structure is in sofa-form.

When the structure is to be converted from sofa-form to bed-form, the cushion L is removed. The front bed-section is then lifted and drawn forwardly, the springs I assisting in this action.

After the structure has been unfolded, the top section of the folded mattress is thrown forwardly to rest upon the bed-bottom E', it being noted that the sections of the mattress G are connected by a hinge-portion 20 (Fig. 1).

In converting from bed-form to sofa-form, the front section of the mattress is folded back onto the rear section, after which the structure is folded in an obvious manner. After the folding operation, the seat-cushion is placed upon the spring bed-bottom E' with which the front bed-section is equipped. The short arms of the levers D are equipped with stops 3^a adapted to support the lever C in the folded condition of the structure, as 120 shown in Fig. 4.

The construction is strong and durable, may be operated with ease, and may be manufactured at moderate cost. It provides for the housing of a mattress, or a mattress and other bedding between the two bed-sections in the folded condition of the structure.

The front bed-section remains upright, or non-invertible in converting the structure from one form to another. This front bed-

section is carried by the levers C and D by practically a parallel movement. On the other hand, the rear bed-section is given an undulating movement in the operations of 5 raising and lowering it, as will be understood from Fig. 3. This permits the structure to pass the lower corner of the back A², it being noted that the back overhangs the rear portion of the space in the base- 10 portion of the main frame in which the folded structure is housed in the manner shown in Fig. 4.

The foregoing detailed description has been given for clearness of understanding 15 only, and no unnecessary limitations should be understood therefrom, but the appended claims should be construed as broadly as permissible, in view of the prior art.

What I regard as new, and desire to secure 20 by Letters Patent, is:

1. In a sofa-bed; a main frame; a front pair of angular levers and a rear pair of angular levers adjacent the ends of said frame; means for pivotally connecting the ends of 25 the short arms of said levers to the frame; a rear bed-section mounted on said short arms, the short arms of the front levers being at an angle to the short arms of the rear levers and of a different length; and a front 30 bed-section mounted on the long arms of said levers.

2. In a sofa-bed; a main frame; a front pair of angular levers and a rear pair of angular levers adjacent the ends of said frame; 35 means for pivotally connecting the ends of the short arms of said levers to the frame; slides pivotally mounted on the elbow-portions of said levers, the short arms of the front levers being of less effective length 40 than the short arms of the rear levers; a rear bed-section mounted on said slides; and a front bed-section mounted on the long arms of said levers.

3. In a sofa-bed; a main frame; a rear bed- 45 section; a front bed-section; front and rear pairs of angular levers having elbow portions carrying the rear bed-section and long arms carrying the front bed-sections, one set of arms of one of said pairs of levers being 50 shorter than the corresponding set of arms of the other pair and set at an angle with respect thereto, for the purpose set forth; and means for pivotally mounting the levers on the ends of the frame.

55 4. In a sofa-bed in folded condition: a main frame; a front pair of angular levers having short arms forming a given angle with respect to the long arms; a rear pair of angular levers having short arms forming a 60 larger angle with respect to the long arms, means for pivotally connecting the free ends of all of the short arms of the levers with the main frame; slides pivotally connected with the elbow-portions of said levers, the effective 65 short arms of the rear levers being of

greater length than the effective short arms of the front levers; a rear bed-section mounted on said slides; and a front bed-section mounted on the long arms of said levers.

5. In a sofa-bed: a main frame; front and 70 rear pairs of angular levers, the short arms of one pair being inclined upwardly and rearwardly and the short arms of the other pair being inclined forwardly and upwardly in the extended condition of the structure; 75 means for pivotally connecting the free ends of the short arms of said levers to the frame; a rear bed-section mounted on the elbow-portions of said levers; and a front bed-section mounted on the long arms of said levers. 80

6. In a sofa-bed: a main frame; a front pair of angular levers and a rear pair of angular levers, the front pair of levers having short arms of less length than the short arms of the rear levers and disposed at an angle 85 with relation thereto; means for pivotally mounting the levers on the frame; slides mounted on the elbow-portions of said levers; a rear bed-section mounted on said slides; a front bed-section mounted on the 90 long arms of said levers; and means for preventing undue shifting of the rear bed-section with respect to said slides during the opening and closing of the structure.

7. In a sofa-bed structure: a main frame; 95 a front pair of angular levers having short arms; means for pivotally mounting the ends of the short arms on the frame; a front pair of slides; pivotal connections between said slides and the elbow-portions of said levers 100 spacing said slides from said levers; a rear pair of angular levers having short arms and having long arms adapted to rest upon the pivotal connections in the extended condition of the structure; means for pivotally mounting the ends of the short arms of said rear levers on the frame; slides mounted on the 105 elbow-portions of said rear pair of levers; a rear bed-section mounted on said slides; and a front bed-section pivotally connected 110 with the free ends of the long arms of said levers.
